UNITED STATES PATENT OFFICE.

JOSEPH A. ANGLADA, OF NEW YORK, N. Y., ASSIGNOR, BY MESNE ASSIGNMENTS, TO
EMIL M. LOWY, OF NEW YORK, N. Y.

INTERNAL-COMBUSTION ENGINE.

1,229,568.

Specification of Letters Patent. Patented June 12, 1917.

Application filed February 24, 1916. Serial No. 30,112.

To all whom it may concern:

Be it known that I, JOSEPH A. ANGLADA, a citizen of the United States, residing at New York, county and State of New York, 5 have invented certain new and useful Improvements in Internal-Combustion Engines, of which the following is a full, clear, and exact description.

This invention relates to internal combustion engines, and has particular reference to the valves of such engines.

An object of the invention is to provide a rotary distributing valve which will be displaced or reciprocated during its rotary 15 movement with resultant continual polishing of its seats.

A further object is to provide adequate cooling of the valve to compensate for the additional reciprocatory movement.

20 A still further object is to provide a valve of the above described construction which will be of minimum magnitude for its purpose, thereby decreasing weight and friction, with corresponding increase in efficiency.

25 The invention can be readily understood from the following description taken in connection with the accompanying drawing, in which—

Figure 1 is a fragmentary side elevation, 30 partly in section, showing an internal combustion engine embodying my improvements.

Fig. 2 is a fragmentary side elevation, 35 partly in section, showing a modified form of the invention.

Referring now to the drawing in which like characters of reference designate similar parts, 10 designates a cylinder which is provided near its upper or outer end with an exhaust port 11 and an admission port 12. The cylinder is provided with a water jacket 13. A sleeve valve 14 is mounted coaxial with and outside of the cylinder and rotates on the wall of the water jacket and flanges 40 15—16 thereof, as a seat. In the valve is provided a port 17 which registers alternately with the ports 11 and 12. The valve is rotated continuously to cover or uncover the inlet and exhaust ports in the cylinder in 45 proper sequence, by means of a gear 18 on the valve, and in the present embodiment this gear is shown as being driven at a positive ratio from the crank shaft 19 of the engine by means of a shaft 20 geared to the 50 crank shaft and to the gear 18 as shown.

During rotation the valve is displaced or reciprocated to continuously polish the seat thereof, and this reciprocating movement may be accomplished in any preferable way, but for convenience I have shown a projection 21 formed on the seat 15 of the valve, the projection operating in a cam way 22 on the valve and serving to lift the valve at times during its rotary movement. To make the return stroke of the valve positive, the 60 valve may be formed with a projection 23 which operates in a cam way 24 on the seat 16. Or as shown in Fig. 2, I may form a cam way 25 in the nature of a groove, in which operates a projection 26 in the nature of a 70 pin on the valve seat 27.

In order to reduce the magnitude of the valve to a minimum, as shown in Fig. 2, the cylinder is decreased or reduced in diameter, as shown at 28, beyond the limit of stroke of 75 the piston 29, and the exhaust and admission ports 30 and 31 are located in this reduced end of the cylinder. The continuously rotated valve 32 surrounds this reduced end of the cylinder and is formed with a port 33 80 which alternately registers with the exhaust and inlet ports of the cylinder during rotation of the valve.

I have shown, in Fig. 1, the water jacket 85 for the cylinder located inside of the valve, and this construction I have reproduced as shown at 34 in Fig. 2, and I also may dispose a water jacket outside of the valve as shown at 35, if desired, to provide adequate cooling of the valve to compensate for the additional 90 reciprocatory movement of the valve.

While I have described a specific embodiment of my invention, I do not limit myself to the exact construction shown as there is a wide range of modifications which may be 95 resorted to within the scope of the appended claims.

I claim:

1. In an internal combustion engine, a 100 ported cylinder, a ported valve member coaxial with the cylinder, means for rotating the valve member, a seat member therefor, means for reciprocating the valve member relatively to the seat member, including a cam way formed on one member and a projection on the other member, operating in 105 the cam way.

2. In an internal combustion engine, a 110 ported cylinder, a ported valve member coaxial with the cylinder and having a con-

- tinuous cam way, a seat member, a projection on the seat member operating in said cam way to reciprocate said valve member, and means for rotating said valve member.
5. In an internal combustion engine, a cylinder having a ported end of reduced diameter, a revoluble ported valve member coaxial with the cylinder outside of said end, a seat member for the valve member, a continuous cam way on one of said members, and means on the other member operating in said cam way to reciprocate said valve member during rotation thereof.
10. In an internal combustion engine, a cylinder, a water jacketed ported valve outside 15 of said cylinder, means for continuously rotating the valve, and means for displacing the valve.
5. In an internal combustion engine, a ported cylinder, a ported valve, said valve 20 being water jacketed inside and outside, means for rotating the valve, and means for reciprocating the valve.

Signed at New York, county of New York, State of New York, this 23rd day of 25 February, 1916.

JOSEPH A. ANGLADA.
